UNITED STATES PATENT OFFICE.

JULIUS A. MAHR, OF MINNEAPOLIS, MINNESOTA.

FORGING AND ANNEALING FURNACE.

1,285,761.

Specification of Letters Patent. Patented Nov. 26, 1918.

Application filed May 25, 1916. Serial No. 99,764.

To all whom it may concern:

Be it known that I, JULIUS A. MAHR, a citizen of the United States, residing at Minneapolis, in the county of Hennepin and State of Minnesota, have invented certain new and useful Improvements in Forging and Annealing Furnaces; and I do hereby declare the following to be a full, clear, and exact description of the invention, such as will enable others skilled in the art to which it appertains to make and use the same.

My invention relates to improvements in forging and annealing furnaces; and, to this end, it consists of the novel devices and combinations of devices hereinafter described and defined in the claims.

In the accompanying drawings, which illustrate the invention, like characters indicate like parts throughout the several views.

20 Referring to the drawings,

Figure 1 is a front elevation of a furnace having the invention incorporated therein, some parts being broken away and some parts being shown in section;

25 Fig. 2 is a vertical longitudinal central section;

Fig. 3 is a horizontal section taken on the irregular line $x^3 x^3$ of Fig. 2;

Fig. 4 is a detail view in section taken 30 on the line $x^4 x^4$ of Fig. 1;

Fig. 5 is a detail view in section taken on the line $x^5 x^5$ of Fig. 1; and

Fig. 6 is a fragmentary detail view, with some parts sectioned on the line $x^6 x^6$ of 35 Fig. 1.

In the drawings, the invention is shown incorporated in a rivet forging furnace comprising a housing 1, supported on relatively long legs 2 and having at one end an outwardly and downwardly projecting extension 3. The housing 1 and its extension 3 are made up of a sectional cast metal casing open at its top and a lining of fire brick or other refractory material, which affords 45 the sole top for the housing.

Formed in the housing 1, is a heating chamber 4 having a door opening 5, formed in the front wall of said housing, and also having a deflecting surface 6 extending from the top thereof, part way down onto one of its sides, to wit: the one opposite the extension 3. An oblique combustion chamber 7 extends completely through the housing ex-

tension 3 and has communication, at its upper end, with the heating chamber 4 through a passageway 8, located at the top of said heating chamber. Also formed in the housing extension 3, is an auxiliary air intake passageway 9, the receiving end portion of which extends parallel to the combustion chamber 7 and the delivery end portion of which extends horizontally slightly below the top of the heating chamber 4 and opens into the combustion chamber 7, at the passageway 8.

An air chest 10 is bolted or otherwise rigidly secured to the lower end of the housing extension 3 and is provided with a nozzle 11, which extends into the lower end of the combustion chamber 7. A port 12, in the air chest 10, connects the chamber thereof with the auxiliary intake passageway 9.

Air is delivered into the air chest 10, through a pipe 13, under pressure, from a blower, indicated as an entirety by the numeral 14. This pipe 13 extends in front of the housing 1 and its extension 3 and has interposed therein an air preheater 15 and an oil preheater 16. The air preheater 15 is 75 in the form of a casting bolted to the front of the housing 1, above the bottom of the door opening 5 and is spaced slightly outward from the front face of said housing. This air preheater 15 has a relatively narrow vertically extended chamber into the lower portion of which the delivery end of the pipe 13 opens and from the upper portion of which leads the delivery end portion of said pipe. The pipe 13, from the air preheater 15 to the air chest 10, extends downward and has interposed therein the oil preheater 16. This oil preheater 16 forms a section 80 of the pipe 13 and has formed in its underside a segmental oil chamber 17.

An oil pipe 18, leading from a storage tank or other suitable source of supply, not shown, has its delivery end secured to the oil preheater 16 and arranged to discharge into the lower end portion of its chamber 90 17. The oil from the pipe 18 passes upward through the inclined chamber 17 and into a pipe 19, having a nozzle 20 secured to its delivery end. This nozzle 20 extends completely through the air chest 10, air nozzle 105 11 and projects into the combustion chamber

7. By reference to Fig. 2, it will be noted that the oil passageway, at the delivery end of the nozzle 20, is curved upward, so that the oil discharged therefrom will flow over 5 the end of the nozzle 20 and be carried therefrom with the air discharged from the nozzle 11. The oil nozzle 20 has screw-threaded engagement with the shell of the air chest 10 and is held thereby co-axial with the 10 nozzle 11 and with freedom for axial adjustment therethrough. A valve 21, interposed in the oil pipe 19, is provided for controlling the supply of oil to the nozzle 20. Also interposed in the oil pipe 19, at 15 the lowest point thereof, is a drip-cock 22.

The supply of air from the pipe 13 to the air chest 10 is controlled by a valve 23, mounted for axial sliding movement in segmental guides 24, formed on opposite walls 20 of the air chest 10, and said valve arranged to seat against the shell of the air chest 10 to close the delivery end of the pipe 13. The stem of the valve 23 extends through the shell of the air chest 10 and has screw-threaded engagement therewith. The air supply from the air chest 10 to the nozzle 11 is controlled by a valve 25, mounted for axial sliding movement on the nozzle 20 and arranged to seat against the shell of 25 the air chest 10 to close the air nozzle 11. This valve 25 is moved axially on the nozzle 11 by a stem 26 eccentrically swiveled thereto, extended through the shell of the air chest 10 and in screw-threaded engagement 30 therewith. A valve 27 is also provided for controlling the auxiliary air supply through the port 12. This valve 27 is arranged to seat against the shell of the air chest 10 to close the port 12 and its stem extends through 35 the shell of said air chest and has screw-threaded engagement therewith. All of the stems of the valves 23, 25 and 27 have, on their outer ends, hand pieces by which the said stems may be turned to carry the respective valves axially toward and from their 40 seats. A lock nut 28 has screw-threaded engagement with each valve stem and is arranged to be turned into engagement with the shell of the air chest 10 to lock the respective valve where set.

A branch air pipe 29 leads from the lower portion of the air preheater 15 and has secured to its delivery end a long horizontal nozzle 30, located slightly below the 55 bottom of the door opening 5 and directly under said air preheater. This nozzle 30 is provided, at its top surface, with a multiplicity of longitudinally spaced holes 31, through which air is forced, under pressure, 60 to form a curtain of air in front of the door opening 5. Obviously, this curtain of air drives the flames and heat, coming through the door opening 5 from the heating chamber 4, upward against the air preheater 15. 65 This deflecting of the flames and heat serves

a double purpose, to wit: keeping the flames and heat out of the operator's face and directing the same against the air preheater 15, for heating the air passing therethrough. Mounted in the pipe 29, is a valve 32 by 70 which the air to the nozzle 30 may be controlled.

Formed in the lower end of the housing extension 3, and opening into the combustion chamber 7, is a clean-out recess 83 75 normally closed by a metal block 34, held in position by co-operating lock elements 35. A clean-out opening 36 is formed in the casting of the housing extension 3 in alignment with the horizontal portion of the auxiliary 80 intake passageway 9 and is normally closed by a cover 37.

The operation of the invention may be briefly described as follows:—

The air, forced through the pipe 13 by the 85 blower 14, first enters the chamber in the air preheater 15, is spread out therein in a relatively thin vertical sheet and its movement through said preheater is sufficiently retarded, owing to the increased size of the 90 preheater 15 over the pipe 13, to allow the air to be heated to the required temperature. A portion of the air from the preheater 15 is forced through the pipe 29, into the nozzle 30, and escapes through the holes 31, 95 forming a curtain of air in front of the door opening 5, the purpose of which has been previously stated. As the hot air rises in the chamber of the preheater 15, the same continues its movement through the pipe 13, 100 oil preheater 16 and into the air chest 10.

The liquid fuel from the pipe 18 enters the chamber 17 of the oil preheater 16, is spread out therein in a thin segmental sheet surrounding the air passage through said preheater and is heated by the air passing from the air preheater 15 to the air chest 10. The movement of the liquid fuel, through the chamber 17, is also retarded in a like manner with the air passing through the air 110 preheater 15. The heated liquid fuel, rising in the chamber 17, enters the pipe 19 and is conveyed therethrough to the air chest 10.

The nozzles 11 and 20 form an atomizer for the fuel mixture, which ignites in the 115 combustion chamber, and the flame thereof strikes the top of the heating chamber 4, moves thereover to the deflector 6, which carries the flame onto the bottom of said heating chamber. The auxiliary air supply, 120 upon leaving the passageway 9, moves transversely into the flame in the combustion chamber 7, thoroughly commingles therewith to assist in increasing the efficiency of the furnace. After the valves 25 and 27 125 have been properly set, it is not necessary to change the same from day to day. The oil supply may be closed by the valve 21 and the air supply by the valve 23.

By preheating the air and oil in the man- 130

ner above described, the efficiency of the liquid fuel for the above described furnace is greatly increased.

What I claim is:—

- 5 1. A metal heating furnace comprising a heating chamber, a combustion chamber, an auxiliary air supply passageway, an air chest having a nozzle arranged to deliver air into the combustion chamber, an oil nozzle extending into the air nozzle, and a valve mounted on the oil nozzle for controlling the air nozzle.
- 10 2. In a furnace of the kind described, the combination with a housing having an outwardly and downwardly projecting extension, said housing having a heating chamber and said extension having a combustion chamber and an auxiliary air intake passageway, said combustion chamber and auxiliary air intake passageway having a common delivery into the heating chamber, of an air chest applied to the lower end of said extension and having an air nozzle extend-

ing into the combustion chamber and a port leading to the auxiliary air intake passage- 25 way, an oil nozzle extending through the air nozzle, and a valve for closing said port.

3. A metal heating furnace comprising a housing having a heating chamber, a combustion chamber, an auxiliary air intake passageway, said combustion chamber and auxiliary air intake passageway having a common delivery into the heating chamber, an air chest having an air nozzle extending into the combustion chamber, a communicating 30 port between the air chest and auxiliary air intake passageway, an oil nozzle extending through the air nozzle, and a valve for closing said port.

In testimony whereof I affix my signature 40 in presence of two witnesses.

JULIUS A. MAHR.
